Primary Examiner — Austin Murphy(74) Attorney, Agent, or Firm — Michael Best & Friedrich
LLP(57) CLAIM

We claim the ornamental design for a stapler cover, as shown and described.

DESCRIPTION

FIG. 1 is a left-side perspective view, taken from the front, of a stapler cover embodying the present invention.

FIG. 2 is a left-side view of the stapler cover.

FIG. 3 is a top view of the stapler cover.

FIG. 4 is a front view of the stapler cover; and,

FIG. 5 is a rear view of the stapler cover.

The portions of the stapler shown in broken lines illustrate environment and form no part of the claimed design. The right-side view opposite FIG. 2 is a mirror image of FIG. 2 and is not shown.
